UNITED STATES PATENT OFFICE.

WILLIAM A. COTNAM, OF NORWALK, IOWA.

LIQUID-DISPENSING DEVICE.

1,250,976.

Specification of Letters Patent. Patented Dec. 25, 1917.

Application filed February 8, 1915. Serial No. 75,926.

To all whom it may concern:

Be it known that I, WILLIAM A. COTNAM, a citizen of the United States, and a resident of Norwalk, in the county of Warren and State of Iowa, have invented a certain new and useful Improvement in Liquid-Dispensing Devices, of which the following is a specification.

My invention relates to improvements in liquid dispensing devices, and it consists in the combinations, constructions, and arrangements herein described and claimed.

An object of my invention is to provide a device which is primarily intended to dispense gasoline but which does not require the services of an attendant, the purchaser drawing out the gasoline, while means is provided for indicating the amount so drawn in the office or store of the concern which sells the gasoline.

A further object of my invention is to provide a dispensing apparatus in which a main tank may have the liquid pumped out of it automatically into an auxiliary tank, from which latter tank the liquid is drawn, with means for starting up and shutting off the pump, so as to keep the auxiliary reservoir practically filled.

A further object of my invention is to provide a novel means, including a float valve having connections for breaking or closing a circuit to the electric motor which runs the pump.

Other objects and advantages will appear in the following specification and the novel features of the invention will be particularly pointed out in the appended claims.

My invention is illustrated in the accompanying drawing forming part of this application, and in which—

Figure 1 is a side view of the apparatus, certain parts being shown in section.

Fig. 2 is a side view in detail of a valve member.

Fig. 3 is a bottom view of the member shown in Fig. 2.

Fig. 4 is a central sectional view through the auxiliary tank, and

Fig. 5 is a side view of a portion of the tank showing the circuit breaking device.

In carrying out my invention I provide a main storage tank 1, see Fig. 1. This tank is preferably located under ground and has surmounting it a pressure tank 2. The latter may communicate with the storage tank

1, but is preferably shut off from communication by means of a valve 3.

An auxiliary reservoir or tank 4 which is designed to be considerably smaller than the storage tank 1, may be disposed in the office or store of the concern which sells the gasoline. A pipe 5 leads from the bottom of the storage tank 1 to a pump P, while a pipe 6 leads from the pump into the bottom of the auxiliary tank. A discharge pipe 7 leads out from the bottom of the auxiliary tank 4 into a dispensing stand 8 which is provided with a flexible hose 9 having a cock 10 and a nozzle 11. A branch pipe 12 is shown as leading to the garage, a three-way valve 13 being provided in the pipe 7 so as to turn the flow of liquid into the pipe 12 at will.

At the upper end of the tank 4 is a valve casing 14 which contains a piston valve 15 like that shown in detail in Figs. 2 and 3. It will be seen that this valve 15 has downwardly projecting arms or fingers 15a which form a cage for a float 16, this float being made of aluminum, copper, or any suitable material. The float 16 is really a ball valve, for it is designed to stop a passage 17 in the valve 15, see Figs. 2 and 4, when in the dotted line position shown in Fig. 4. The valve stem 18 of the piston 15, has secured to it an arm 19 which is secured in turn to a rod 20 which is slidably disposed in guide members 21 and 22, and which bears a contact member 23 arranged to engage the contact members 24 and 25 which are carried by an insulating base 26 secured to the side of the tank 4. The contact 23 is insulated from the rod 20 as shown.

The lower end of the rod 20 is connected by means of a link 26 to a crank arm 27 which is on a rock shaft 28 which is supported in bearings 29 and 30. One of these bearings, for instance, the bearing 30, is provided with teeth 31 and is in fact a clutch member which is arranged to cooperate with a clutch member 32 which is secured to the rod 28. A spring 33 bears at one end on the bearing 29 and at the other end on a pin 34 carried by the rod 28. A thumb wheel 35 is for the purpose of manipulating the rod 28.

A pipe 36 connects at the top with the valve casing 14 and at its bottom with the pressure tank 2. A gage glass 37 is provided on the outside of the auxiliary tank

4, the scale 38 of the gage glass being preferably marked in gallons. A pressure gage 39 is provided for ascertaining the pressure within the auxiliary cylinder 4.

From the foregoing description of the various parts of the device, the operation thereof may be readily understood. Let us assume that the tank 1 is filled with liquid to the height indicated in Fig. 1, and that the auxiliary tank 4 is empty. Now by closing the switch S, the motor M will run the pump P to cause the latter to force liquid from the storage tank 1 into the auxiliary tank 4. As the liquid passes into the auxiliary tank, the air is forced through the pipe 38 into the pressure tank 2, so that the pressure is continually rising and is used for forcing the liquid out of the tank 4 when the outlet pipe 7 is opened, as described later. This air, it will be observed passes by way of the passage 17 in the valve stem 18. Now when the liquid reaches the float 16, the latter will be carried up until it closes the passage 17, whereupon the piston 15 will act as a solid piston and will rise under the pressure. This movement will cause the breaking of the motor circuit by lifting the bridging member 23 out of engagement with the contacts 24 and 25.

During the upper movement of the rod 20 which is secured to the arm 19 carried by the valve stem 18, the shaft 28 was given a rotative movement in a clockwise direction, looking at the end of the shaft shown in Fig. 3. The clutch or ratchet portion 32 during this movement is turning idly over the teeth 31 of the bearing member 30 owing to the manner in which the teeth are inclined. Reverse movement of the shaft 28 is prevented until the wheel 35 is manipulated in the manner described hereinafter.

The tank 4 is now full and ready for the dispensing of the liquid. The customer turns the cock 10 and draws off gasoline from the tank 4. As stated before, the tank 4 may be located in the office, so that the clerk or bookkeeper may note the amount of gasoline which the customer draws out, so that when the latter comes into the store to pay for it, the clerk can make a proper charge.

As the liquid recedes from the float, the latter falls, letting the pressure in the pipe 38 have access to the interior of the auxiliary tank 4 and driving out the liquid. Now when the clerk observes that the tank is nearly empty, all that is necessary for him to do is to push inwardly on the button or handwheel 35. This will free the clutch members 32 and 31 whereupon the springs 33 and 33^a which are under tension will tend to bring the crank arm and the rod 20 into position shown in Fig. 5. In this figure the contact member 23 is shown engaging the contact members 24 and 25, whereupon the

circuit through the motor M will be established, thus causing it to pump again from the storage tank into the auxiliary tank. The clerk need pay no further attention to the device, since the current will be automatically cut off as before stated.

If any of the gasoline should get past the valve 15 and should be forced over into the pipe 38, it will run down into the pressure tank 2. When sufficient gasoline accumulates in this tank, it may be led into the main storage tank by opening the cock 3.

It will be seen that the tank 2 is an important feature of this invention. The liquid in the tank 4 is not only under the action of gravity, but also is subjected to the pressure in the tank 2, so that when the stop cock 10 in the nozzle 11 is opened, the gasoline is immediately forced out, no matter whether the delivery hose 9 is above or below the tank 4. Without the tank 2 the pump would have to work every time a portion of the gasoline was drawn off. In the present construction, the tank 4 may hold a large supply, so that the pump may be of small capacity. Obviously, as much of the liquid may be drawn off from the tank 4 as desirable, by using a larger or a smaller delivery pipe, regardless of the capacity of the pump, since the latter may be working for some time to fill the tank, or which may be emptied at a rapid rate.

It will be seen by the use of this device, the attendant who is usually necessary, need not be present. There is, therefore, a saving of labor and a corresponding economy of operation. In Fig. 1 I have shown the auxiliary tank as located above the ground and above the dispensing stand, but it will be understood that this tank may be located in any suitable position, since the liquid dispensed therefrom is forced out by pressure and not by gravity.

It will be understood that the lateral movement of the crank rod is comparatively slight and that while it has both a rotative and a lateral motion, these motions are so slight that a slight looseness in the mountings of these parts is entirely sufficient to compensate for the double movement.

I claim:

1. In a liquid dispensing apparatus, a main storage tank, an auxiliary tank, a stop cock for drawing off the liquid from the auxiliary tank, a pressure tank disposed between said storage tank and said auxiliary tank, and having connections with both of said tanks, a pump for pumping fluids from said main storage tank into said auxiliary tank, a motor for operating the pump, a circuit breaker in the motor circuit, a piston valve disposed in said auxiliary tank for controlling the connection between the pressure tank and the auxiliary tank, a float for controlling said piston valve, a slidable rod

connected with said piston for operating the circuit breaker, and means for manually opening the piston valve and for simultaneously closing the motor circuit.

2. In a liquid dispensing device, an auxiliary tank, a stop cock for drawing off the liquid from the auxiliary tank, a storage tank, a pump for pumping liquid from said storage tank into said auxiliary tank, a piston valve carried by said auxiliary tank, a rod secured to the valve stem of said piston valve and adapted to move therewith, a pair of stationary contacts, a contact carried by said rod and arranged to be brought into and out of engagement with said stationary contacts, and means for retaining the piston valve in any of its shifted positions and for releasing it at will.

3. In a liquid dispensing device, an auxiliary tank, a stop cock for drawing off the liquid from the auxiliary tank, a storage tank, a pump for pumping liquid from said storage tank into said auxiliary tank, a piston valve carried by said auxiliary tank, a rod secured to the valve stem of said piston valve and adapted to move therewith, a pair of stationary contacts, a contact carried by said rod and arranged to be brought into and out of engagement with said stationary contacts, and means for retaining the piston

valve in any of its shifted positions and for releasing it at will, said last named means comprising a rock shaft having operative connection with said shiftable rod, a stationary clutch member, and a clutch member carried by said rock shaft and arranged to engage said stationary clutch member, said rock shaft being shiftable longitudinally to free said clutch member, and a spring for restoring said rock shaft to its original position.

4. In a liquid dispensing apparatus, a main storage tank, an auxiliary tank a stop cock for drawing off the liquid from the auxiliary tank, a pressure tank disposed between said storage tank and said auxiliary tank, and having connections with both of said tanks, a pump for pumping fluids from said main storage tank into said auxiliary tank, a motor for operating the pump, a circuit breaker in the motor circuit, a piston valve disposed in said auxiliary tank for controlling the connection between the pressure tank and the auxiliary tank, said piston also operating said circuit breaker to stop the motor.
